CONTROL MECHANISM FOR RECLINING CHAIRS

Filed Nov. 6, 1929

INVENTOR
CHARLES E. FERREIRA.
By *Arthur L. Lee*,
HIS ATTORNEY.

UNITED STATES PATENT OFFICE

CHARLES E. FERREIRA OF OAKLAND, CALIFORNIA

CONTROL MECHANISM FOR RECLINING CHAIRS

Application filed November 6, 1929. Serial No. 405,136.

My invention relates to improvements in control mechanism for adjusting the inclination of the back of reclining chairs wherein a control bar is assembled as a unit with actuating springs and a guide and stop member for installation under the seat of a chair and arranged to be connected to a pivoted back movable to reclining positions relative to the seat.

10 The present invention consists in an improved construction and arrangement of actuating and control members for reclining chairs of the type disclosed in my co-pending application, Serial Number 145,805, filed November 2, 1926, the primary object being to provide a control mechanism of increased efficiency.

Another object is to provide an improved control mechanism of simple and effective construction which may be constructed, assembled, and installed as a unit.

A further object is to provide an improved device of the character described which will facilitate assembling and installation.

25 A still further object is to provide an improved control mechanism of more rugged and durable construction, and which is more positive and efficient in its operation.

I accomplish these and other objects by means of the improved device disclosed in the drawings forming a part of the present application wherein like characters of reference are used to designate similar parts throughout the specification and drawings, and in 35 which—

Fig. 1 is a side elevation of my improved control mechanism as applied upon a reclining chair, the near side member of the chair being removed;

40 Fig. 2 is a side elevation of my improved control unit, partly in vertical section;

Fig. 3 is a broken front elevation of the device as shown in Fig. 2; and

45 Figs. 4 and 5, are broken detail views showing modified forms of retaining notches upon the control bar.

Referring to the drawings, the numeral 1 is used to designate in general a chair frame having a back frame 2 pivotally mounted 50 thereon as at 3 for angular adjustment rela-

tive to the usual seat provided in such chairs and supported at the front by a transverse frame member 4 in the ordinary manner. The back frame 2 is provided with downwardly disposed extensions 6.

55 In my present invention, my improved control mechanism consists of a control bar 7 slidably mounted for longitudinal movement through a guide member 8 having a slot 9 arranged to receive the bar 7. The bar 7 has a plurality of notches or teeth 11 formed upon the upper edge thereof and arranged 60 to engage a rigid stop portion 12 formed at the top of the slot 9. A downwardly and forwardly extending foot pedal 14 is connected to the forward end of the bar 7 and a downwardly disposed extension 16 having 65 an opening 17 therein is connected to the rearward end of the bar 7. The bar 7 is preferably formed from cast metal with the 70 pedal extension 14 and the apertured extension 16 cast integrally therewith as shown in the drawings.

75 The guide member 8 is preferably tubular in form and threaded at each end. The slot 9 is cut diametrically across the body of the member 8 from one end thereof, the slot being cut to a greater depth upon one side than upon the other to form the stop 12 adjacent the top and upon the rearward side of 80 the member 8. The upper end of the member 8 is threaded into a flange fitting 17 whereby the guide may be secured upon the under side of the member 4 under the chair seat. The lower end of the guide member 8 is provided with a cap 18 closing the lower 85 end of the member and its slot 9 and retaining a spring 19 within the lower portion of the member 8 to normally press the bar 7 into engagement with the stop 12.

90 A spring guide rod 21 is connected at its forward end to the lower end of the guide member 8, and arranged to extend rearwardly through the opening 17 in the extension 16 substantially parallel to the bar 7. The rod 21 is preferably tapped into the side 95 of the cap 18 and secured thereto by means of a jam nut 22 threaded onto the rod 21 and tightened against the cap. A compression coil spring 23 is mounted around the rod 21, 100

said spring being compressed between the guide member 8 and the extension 16 to normally move the control bar 7 rearwardly relative to the guide member. The pressure of the spring 23 is adjusted by means of an adjusting nut 24 threaded upon the forward end of the rod 21 adjacent the jam nut 22 and forming an abutment for the spring 23 at the fixed end thereof.

10 The control bar 7 is connected to the back frame 2 by means of a pair of connecting members 26 rigidly secured to the bar 7 adjacent the rearward end thereof by suitable securing members 27, the rearward ends of 15 said members 26 being pivotally connected as at 28 to the lower ends of the extensions 6 of the back frame.

The control mechanism is constructed and assembled as a unit wherein the control bar 20 7, and the springs 19 and 23 are mounted upon the guide member 8. The spring 23 holds the member 7 in its extreme rearward position as defined by the pedal 14, which, in said extreme position, preferably abuts 25 against the guide member 8. At the same time, the spring 19 seats the bar with the stop 12 engaged by the outermost notch or tooth 11. The assembled structure forms a light and compact structure which may be 30 readily secured upon a chair frame by means of the flange fitting 17 without disturbing the adjustment of the assembled mechanism. The connecting members 26 may be secured to the rearward end of the bar 7 either before or after the device has been mounted 35 upon a chair.

In operation, my improved control mechanism, assembled upon a chair as herein disclosed, provides a simple and convenient 40 means for adjusting the reclining position of the seat back. In normal position the control bar 7 occupies its extreme rearward position, thereby holding the back 2 in its normal upright position by means of the 45 connections 26. In this position, the outermost notch or tooth 11 of the bar 7 engages the stop 12. If it is desired to move the back to a reclining position, the pedal 14 is depressed by the heel of an occupant of the 50 chair, thereby depressing the bar 7 and moving the tooth or notch 11 out of engagement with the stop 12. The weight of an occupant leaning rearwardly against the seat back will now cause said back to swing rearwardly, and in so doing will move the bar 7 forwardly through the guide member 8 against the pressure of the spring 23. When the pedal 14 is released, the bar 7 will be moved upwardly by the spring 19 to cause 55 a desired tooth or notch 11 to engage the stop 12. Further forward movement of the bar 7 will thus be prevented by the notch 11 engaged.

In the preferred form of retaining notch or 60 tooth 11, the bottom part of each notch

is cut square to seat upon the stop 12, while the upper portion of each tooth is inclined toward the forward end of the bar as shown in Figs. 1 and 2. In this construction, the lower portion of the notch forms a seat which will effectually hold the seat back 2 against movement in either direction. A slight depressing of the pedal will move the notch to disengage the stop 12, thereby permitting the spring 23 to advance the bar 7 to its normal position and thereby return the back 2 to its normal upright position when relieved from the weight of the occupant.

70 In Fig. 4 I have shown a tooth structure 75 wherein the notches 11 are formed as forwardly faced ratchet teeth. When any tooth 11 engages the stop 12, rearward tilting of the back is prevented by the forward face of a tooth 11 against the back of the stop 12. When the back is relieved from the weight of an occupant the spring immediately and automatically returns the bar 7 and back 2 to normal positions.

80 In Fig. 5 I have shown a square cut notch 85 11. Each notch in this form will operate to hold the back 2 in a desired adjusted position, regardless of whether the weight of an occupant is imposed upon the back. In this last 90 mentioned form, as well as in the preferred 95 form, each notch or tooth 11 defines a fixed position of the bar and back in which said bar and back may be retained until released by depressing the pedal.

100 The specific details of construction and materials disclosed in the present application are subject to modification without departing from the spirit of my invention. I therefore desire to avail myself of all modifications which may fall within the scope of the 105 appended claims.

Having thus described my invention what I claim as new and desire to secure by Letters Patent is—

110 1. A control mechanism for reclining 110 chairs comprising the combination with a chair having a back pivotally movable from a normal upright position to reclining positions relative to a seat, of a rigid guide member depending from the front of the seat and provided with a stop portion; a control bar slidably mounted within the guide and having a plurality of retaining notches adapted to engage the stop; means connecting the bar with the back for moving the bar longitudinally through the guide when the back is moved from one position to another; means normally holding the bar in engagement with the stop; means carried upon the forward end of the bar for depressing said bar out of engagement with the stop; a compression spring mounted adjacent to the bar; a fixed abutment carried by the guide member to seat the forward end of the spring; and means carried by the bar and forming a seat for the 120 125 130

rearward end of the spring, said spring operating to normally move the bar and the back to normal positions.

2. A control mechanism for reclining chairs comprising the combination with a chair having a seat pivotally movable from a normal upright position to reclining positions relative to a seat, of a stationary guide member depending from the front of the seat and provided with a rigid stop portion; a control bar slidably mounted within the guide and provided with a plurality of retaining notches adapted to engage the stop portion of the guide; means connecting the rearward end of the bar with the back to move the bar longitudinally when the back is moved from one position to another; means normally holding the bar in engagement with the stop; a foot pedal connected to the forward end of the bar and extending downwardly and forwardly therefrom for depressing the bar out of engagement with the stop; a downwardly disposed extension carried upon the rearward end of the bar; and a compression spring mounted between the guide member and the extension upon the rearward end of the bar to normally move the bar and the back to normal positions.

3. A control mechanism for reclining chairs comprising the combination with a chair having a back pivotally movable, from a normal upright position to reclining positions relative to a seat, of a stationary guide member depending from the front of the seat and provided with a rigid stop portion; a control bar slidably mounted within the guide and provided with a plurality of retaining notches adapted to engage the stop portion of the guide; means connecting the rearward end of the bar with the back to move the bar longitudinally when the back is moved from one position to another; means normally holding the bar in engagement with the stop; a foot pedal connected to the forward end of the bar for depressing the bar out of engagement with the stop; a downwardly disposed extension carried upon the rearward end of the bar; a spring guide secured to the depending guide member and slidably engaged by the downwardly disposed extension of the bar; and a compression spring mounted upon said spring guide and compressed between said extension and the guide member to normally move the bar and the back to normal positions.

4. A control mechanism for reclining chairs comprising the combination with a chair having a back pivotally movable from a normal upright position to reclining positions relative to a seat, of a stationary guide member depending from the front of the seat and provided with a rigid stop portion; a control bar slidably mounted within the guide and provided with a plurality of retaining notches adapted to engage the stop

portion of the guide; means connecting the rearward end of the bar with the seat back to move the bar longitudinally when the back is moved from one position to another; a spring mounted within the lower end of the guide member and normally holding the bar with one of its notches engaging the stop; a foot pedal upon the forward end of the bar for depressing the bar out of engagement with the stop; a downwardly disposed slotted extension formed upon the rearward end of the bar; a spring guide secured at its forward end to the guide member and having its rearward end extending rearwardly through the slotted extension; and a compression spring mounted upon the spring guide and compressed between the guide member and the slotted extension to normally move the bar and the back to normal positions.

5. In a control mechanism for reclining chairs, a control unit comprising a guide member adapted to be mounted in depending position upon the forward edge of a chair seat; a control bar slidably mounted for longitudinal movement through the guide, said bar being provided with a foot pedal extension upon its forward end and with a downwardly disposed slotted extension upon its rearward end; a stop formed upon the guide member; retaining notches formed upon the bar to engage the stop; spring means for moving the bar to engage the stop in any of said notches; a spring guide rod secured at its forward end to the guide member and extending rearwardly through the slotted extension; and a compression spring mounted around the rod and compressed between the guide member and the slotted extension to normally move the bar rearwardly to its extreme position, said spring and bar being assembled upon the guide member as a unit for installation upon a seat bottom to receive connecting means extending from the bar to a pivoted back mounted for reclining adjustment relative to the seat.

6. In a control mechanism for reclining chairs, a control unit comprising a slotted guide member provided with a mounting flange upon its upper end to be secured upon the under side of chair seat; a rigid stop formed upon the guide member at the upper end of its slot; a control bar slidably mounted within the guide slot and having a plurality of notches to engage the stop, said bar being provided with a downwardly and forwardly disposed foot pedal at its forward end and with a downwardly disposed apertured extension at its rearward end; a spring mounted within the guide member to normally move the bar to engage the stop in any of the notches in said bar; a retaining cap upon the lower end of the guide member to retain the spring; a spring guide rod connected at its forward end to the lower end of the guide member and extending rearward-

ly through the apertured extension; and a compression spring mounted around the rod and compressed between the guide member and the apertured extension to normally move the bar rearwardly to an extreme position.

7. In a control mechanism for reclining chairs, a control unit comprising a guide member adapted to be rigidly mounted adjacent the forward edge of a chair seat; a control bar slidably mounted for longitudinal movement in the guide; a foot pedal extension upon the forward end of the bar; a fixed stop upon the guide; retaining notches upon the bar to engage the stop; spring means engaging the bar to move said bar and the notches thereof into engagement with the stop; a spring mounted upon the unit with its forward end rigidly seated adjacent the guide; and means carried by the inner end of the bar to seat the rearward end of the spring, said spring normally moving the bar to its extreme rearward position, and said spring and bar being assembled upon the guide member for installation as a unit upon a chair to receive connecting means connected to the bar and to a pivoted back mounted upon the chair.

8. In a control mechanism for reclining chairs, a control unit comprising a guide member adapted to be rigidly mounted adjacent the forward edge of a chair seat; a control bar slidably mounted for longitudinal movement in the guide; a foot pedal extension upon the forward end of the bar; a fixed stop upon the guide; retaining notches upon the bar to engage the stop; spring means engaging the bar to move said bar and the notches thereof into engagement with the stop; a spring guide rod mounted in spaced relation to the bar and having the forward end thereof secured to the guide; a spring mounted upon the guide rod; and means carried by the rearward end of the bar and movably engaging the rearward end of the spring guide rod, said spring seating upon said means to normally press the rod rearwardly to its extreme rearward position and being compressible by a forward movement of the bar, said spring and bar being assembled upon the guide member for installation as a unit upon a chair to receive connecting means connected to the bar and to a pivoted back mounted upon the chair.

55 In witness whereof, I hereunto set my signature.

CHARLES E. FERREIRA.
